UNITED STATES PATENT OFFICE

FRED A. GERLING, OF BOISE, IDAHO

FLUID PRESSURE ENGINE

Application filed June 4, 1930. Serial No. 459,218.

My invention relates to fluid pressure engines, operating with steam, compressed air, or other gases under pressure, and has particular reference to improvements in the engine shown and described in Letters Patent No. 1,811,579, issued to me June 23, 1931.

In the accompanying drawings, forming a part of this specification, and in which like numerals are employed to designate like parts throughout the same,

Figure 1 is a side elevation of an engine embodying my invention,

Figure 2 is a diagrammatic view of valve actuating mechanism,

Figure 3 is an edge elevation of the pivoted forked levers, for actuating the auxiliary inlet valves,

Figure 4 is a plan view of an operating rod,

Fig. 5 is a side elevation of the same, and,

Figure 6 is a transverse section taken on line 6—6 of Figure 5.

In the drawings, wherein for the purpose of illustration, is shown a preferred embodiment of my invention, the numerals 44 and 45 designate stationary cylinders. Mounted to reciprocate within these cylinders are pistons 46 and 47, respectively, rigidly attached to piston rods 48 and 49, having their inner ends connected with links 53, as described in my co-pending application.

The numerals 58 and 58' designate centralizing levers pivoted at their upper ends, as shown at 59 and pivotally connected with the links 53. The companion centralizing levers 61 and 61', not shown in Figure 2, are connected with the links 53, as shown and described in my co-pending application, and serve to drive the rotary driven element.

The centralizing levers 58 and 58' are employed in operating the valve shifting mechanism which constitutes the present invention.

The cylinder 44, see particularly Figure 2, has an inlet port 72, in communication with a fluid pressure supply pipe 73. This inlet port is covered and uncovered by means of an oscillatory valve 74, turned by a crank 75. The cylinder 44 has an exhaust port 76 covered and uncovered by an oscillatory valve 77, turned by a crank 78. The cylinder

45 has an inlet port 79 covered and uncovered by an oscillatory valve 80, turned by a crank 81. The port 79 is in communication with a fluid pressure supply pipe 82, and pipes 73 and 82 have communication with a common source of fluid pressure. The cylinder 45 has an exhaust port 85, covered and uncovered by an oscillatory valve 86, turned by means of a crank 87.

Valve shifting mechanism is provided to alternately open and close inlet valve 74 and exhaust valve 86, comprising vertically swinging levers 88 and 89, pivotally supported at their lower ends, as shown at 90. These levers are arranged upon the same side of the engine with the centralizing arm 58. The lever 88 is provided at its upper end with a fork 91, having its ends attached to suitably stiff retractile coil springs 92, which extend inwardly for suitable connection with a crank 75, as shown in detail in my co-pending application. The lever 89 has a fork 95, which is connected by identical means, including springs 92 with the crank 87. The levers 88 and 89 are connected by means of a rod 96 pivoted thereto. The exhaust valve 77 is opened and closed by means of a lever 97, connected with the crank 78 by the identical yielding connecting means, described in connection with the lever 88, including the springs 92. The inlet valve 80 is opened and closed by means of a lever 98, connected with the crank 81, by yielding means identical with that described in connection with the lever 88, including the springs 92. The levers 97 and 98 are disposed upon the opposite side of the cylinders 44 and 45, with respect to the levers 88 and 89, and are pivotally supported at their lower ends, as shown at 99, to swing in a vertical plane longitudinally of the cylinders. The levers 97 and 98 are connected by a rod 100. The same resilient means and stops are employed to swing the cranks which turn the inlet and exhaust valves, when they are shifted past dead center and to hold the same in the shifted positions, as described in my co-pending application as shown in said application No. 1,811,579. This means comprises generally a retractile coil spring 103 connecting the cranks 75 and 78.

95

100

Disposed upon opposite sides of the crank 75 are stops 104—105, and disposed upon opposite sides of the crank 78 are stops 106—107. In a similar manner, cranks 81 and 87 are connected by a retractile coil spring 110. Stops 111 and 112 are disposed upon opposite sides of crank 87, and stops 113 and 114 are disposed upon opposite sides of crank 81.

In view of the foregoing description, it will be seen that when the inlet valve 74 of the cylinder 44 is opened, exhaust valve 77 of this cylinder is closed while the exhaust valve 86 of the cylinder 45 is opened and the inlet valve 80 is closed, and vice versa.

The numeral 115 designates a shoe carried by the upper end of the vertical swinging lever 116, which is pivoted between its ends upon the rod 96, as shown at 117. The lower end of this lever is connected with a retractile coil spring 118, the other end of which is attached to an arm 119, secured to the rod 96. A link 120 is pivotally connected with the upper end of the lever 116, as shown at 121, and the link is provided at its outer end with a slot 122, receiving a bolt 123, secured to the arm 124, which is attached to the rod 96. It is thus seen that the spring 118 and associated elements yieldingly oppose the outward swinging movement of the upper end of the lever 116, within limits, but when the end wall of the slot 122 engages the bolt 123, this outward swinging movement of the lever 116 is positively stopped. A shoe 125 is carried by the upper end of the lever 126, which is pivoted to swing in a vertical plane between its ends, as shown at 127, upon the rod 96. A retractile coil spring 128 is secured to the lower end of the lever 126, and is attached to an arm 129, secured to the rod 96. A link 130 is pivoted to the upper end of the lever 126, as shown at 131, and has a slot 132 at its outer end, receiving a bolt 133, carried by an arm 134, secured to the rod 96. It is thus seen that the spring 128 and associated elements yieldingly oppose the outward swinging movement of the upper end of the arm 126, but when the end wall of the slot 132 engages the bolt 133, such outward swinging movement of the lever 126 is positively stopped. The shoes 115 and 125 are arranged upon opposite sides and in the path of travel of a roller or trip element 135, which is mounted upon the centralizing lever 58, at a point near and above the connecting rod 96.

When the centralizing lever 58 is in the vertical or neutral position, the roller 135 is equi-distantly spaced from the shoes 115 and 125, and it is obvious that the roller upon the swinging movement of the centralizing lever 58 will alternately engage the shoes, thereby shifting the rod 96 in opposite directions.

A shoe 136 is mounted upon the rod 100 by the identical means as described in connection with the shoe 115, and a shoe 137 is

mounted upon the rod 100 by the identical means, as described in connection with the shoe 125. These shoes 136 and 137 are disposed upon opposite sides of a roller or trip element 138, carried by the centralizing lever 58'. The centralizing levers 58 and 58' swing in unison, as fully described in my co-pending application.

The shoe 125 is set inwardly in advance of the shoe 137, and the shoe 136 has the same arrangement with respect to the shoe 115.

Rods 140 and 140' are pivotally connected with the lower ends of the centralizing levers 58 and 58', as shown at 141, at a point beneath the trip elements or rollers. These rods 140 and 140' extend in opposite directions toward the inlet pipes of the cylinders. Each rod 140 and 140' is provided with a lug 142, rigidly attached thereto, and extending laterally therefrom. This lug is provided with an aperture for slidably receiving a rod 143, extending longitudinally of the rod 140 or 140'. The rod 143 is provided near its outer end with a shoe 144, rigidly attached thereto, and this shoe has a lateral extension or guide 145, slidable in a longitudinal slot 146 formed in the rod 140. A second shoe 147 is rigidly attached to the rod 143 and has a lateral guide 148, slidable in the slot 146. A collar 149 is rigidly attached to the inner end of the rod 143. A compressible coil spring 149 surrounds the rod 143, between the shoe 147 and guide lug 142, and a compressible coil spring 150 surrounds the rod 143 between the guide lug 142 and sleeve 148.

The numeral 151 designates a lever pivoted at its lower end, as shown at 152, with a stationary arm 153. This lever is provided at its upper end, with a head 154, arranged in the path of travel of the shoes 144 and 147, and this head carries a roller 155, arranged to operate between the arms 156 and 157, of a fork, carried by lever 158, pivoted at 159.

The lever 158 has pivotal connection at 160, with a link 161, which is pivoted at 162 with a crank 163. This crank 163 is connected with an auxiliary oscillatory inlet valve 164. The crank 163 has connection with a retractile coil spring 165, attached to the end of a stationary arm 166. The function of the spring 165 is to quickly throw the valve 164 to the end of its stroke when the crank 163 is swung past dead center in either direction and to retain the valve 164 in this position, until again shifted therefrom.

The operation of the engine is as follows:

With the parts in the relative positions, as shown in Figure 2, exhaust valve 77 of cylinder 44 is closed and inlet valve 80 of cylinder 45, is closed, with inlet valve 74 of cylinder 44 open and exhaust valve 86 of cylinder 45 open. Pistons 46 and 47 are traveling to the right and lever 58 is swinging to the right, shifting rod 140 to the right.

This movement of the rod 140 moves the shoe 144 into engagement with the upper end of the lever 151, swinging it to the right. The swinging movement of the lever 151 moves the roller 155 into engagement with the upper arm 157, swinging the upper end of the lever 158 to the left, and shifting link 161, which in turn swings crank 163 and closes auxiliary inlet valve 164. The closing of the auxiliary inlet valve 164 will cut off the supply of compressed air to the cylinder 144 from the reservoir or tank, and this action is properly timed by the adjustment of the shoe 144 so that the valve 164 is closed at the proper interval, to utilize the expansion of the compressed air in the cylinder 44, acting against the piston 46, the maximum expansion being obtainable throughout the full stroke of the piston. The further traveling of the centralizing lever 58 to the right causes roller 135 to engage and shift the shoe 125, shifting the rod 96 to the right, closing valve 74, and at the same time closing valve 86, of the cylinder 45, as the piston 47 nears the end of its stroke, for producing a compression of the air within the cylinder 45, whereby the compressed air is received at full pressure when the valve 80 of cylinder 45 is opened, valve 77 being then also opened. When the centralizing lever 58 swings to the right, as explained, centralizing lever 58' swings to the right, shifting the rod 140' to the right, causing the inner shoe 147 to engage the head of the lever 151, swinging this lever to the right. The roller 155 now engages the arm 156, swinging lever 158, associated with cylinder 45 to the left. This action of the lever 158 shifts link 161 to the left, and acts upon crank 163, and thereby opens valve 164, prior to the entrance of compressed air into the cylinder 45, when roller 138 shifts shoe 137 and opens the valve 80, which occurs at the moment the piston 47 reaches the end of its out stroke in cylinder 45, and at the same movement opening exhaust valve 77 of cylinder 44. Pistons 46 and 47 having now reached the end of their stroke to the right, begin their stroke to the left, and centralizing levers 58 and 58' begin to swing to the left. Centralizing lever 58' now shifts connecting rod 140 associated with the cylinder 45 to the right, causing the outer shoe 144 carried by rod 140' to engage the upper end of the lever 151. The roller 145 carried by this lever will now engage the inner arm 157 of the forked end of the lever 158, swinging lever 158 to the right thereby closing valve 164 of the cylinder 45, at the moment when the piston 47 reaches the relative reverse position of that occupied by the piston in cylinder 44, when valve 164 was closed, thereby utilizing the expansion of compressed air in the cylinder 45, to the maximum, throughout the entire remaining portion of the stroke of the piston 47. Roller

138 carried by centralizing lever 58' now engages the shoe 136, shifting the rod 100 and associated elements to the left, closing valve 78 of cylinder 44 at the moment piston 46 approaches the end of its left stroke, to compress air within the cylinder 44, preparatory to opening the valve 74, whereby this compressed air will not be wasted by expansion at the beginning of the power stroke of the piston 46. As centralizing lever 58' swings to the left, centralizing lever 58 also swings to the left, shifting rod 140 to the left and bringing shoe 147 into engagement with the head of the lever 151, swinging this lever to the left and causing roller 155 to engage the arm 156, thereby swinging lever 158 to the right, and opening auxiliary inlet valve 164 prior to the opening of the valve 74, when the piston 46 reaches the end of its stroke to the left. Roller 135 is finally brought into engagement with shoe 115 thereby shifting rod 96 to the left, and opening valves 74 and 86. The cycle of operating being completed the pistons 46 and 47 begin their stroke to the right.

It is to be understood that the form of my invention, herewith shown and described, is to be taken as a preferred example of the same, and that various changes in the shape, size and arrangement of parts, may be resorted to without departing from the spirit of my invention, or the scope of the subjoined claims.

Having thus described my invention, I claim:

1. In an engine, a pair of opposed cylinders, main inlet valves for the cylinders, exhaust valves for the cylinders, auxiliary inlet valves for controlling the passage of fluid pressure to the main inlet valves, pistons within the cylinders, piston rod means connecting the pistons, a pair of centralizing levers arranged near the cylinders and connected with the piston rod means, pairs of swinging levers connected with the main inlet valves and the outlet valves, rods connecting the levers in said pairs, pairs of shoes carried by the rods, trip elements carried by the centralizing levers and disposed between the pairs of shoes for co-action therewith to shift the main inlet and outlet valves, and operative connecting means between the centralizing levers and the auxiliary inlet valve for closing the auxiliary inlet valves prior to the closing of the main inlet valves.

2. In an engine, a pair of cylinders, main inlet valves connected with the cylinders, outlet valves connected with the cylinders, auxiliary inlet valves controlling the passage of fluid pressure to the main inlet valves, pistons mounted within the cylinders, piston rod means connecting the pistons, a pair of centralizing levers connected with the piston rod means, pairs of swinging levers connected with the main inlet valves and exhaust

- valves to actuate the same, a pair of connecting rods connecting the swinging levers in such pairs, pairs of shoes carried by the rods, trip elements carried by the centralizing levers and disposed between the shoes to shift the main inlet and outlet valves, pivoted levers connected with the auxiliary inlet valves and having forked ends, actuating pivoted levers having parts to operate within
- 10 said forked ends and swing the pivoted levers, and means connected with the centralizing levers to engage and operate the actuating pivoted levers to shift the auxiliary inlet valves.
- 15 3. In an engine, a pair of cylinders, main inlet valves for the cylinders, outlet valves for the cylinders, auxiliary inlet valves for controlling the passage of fluid pressure to the main inlet valves, pistons within the
- 20 cylinders, piston rod means connecting the pistons, centralizing levers connected with the piston rod means, means actuated by the centralizing levers for operating the main inlet valves and exhaust valves, pivoted levers
- 25 having forked ends and connected with the auxiliary inlet valves, pivoted actuating levers having rollers to engage within the forked ends of the pivoted levers, rods pivotally connected with the centralizing levers,
- 30 and a pair of spaced shoes carried by each rod and adapted to alternately engage the corresponding pivoted actuating lever to shift the same.
4. In an engine, a pair of cylinders, main
- 35 inlet valves for the cylinders, outlet valves for the cylinders, auxiliary inlet valves for controlling the passage of fluid pressure to the main inlet valves, pistons within the cylinders, piston rod means connecting the pis-
- 40 tons, centralizing levers connected with the piston rod means, means actuated by the centralizing levers for operating the main inlet valves and the exhaust valves, pivoted levers having forked ends and connected with the
- 45 auxiliary inlet valves, pivoted actuating levers having rollers to engage within the forked ends of the pivoted levers, rods pivotally connected with the centralizing levers and extending near the pivoted actuating
- 50 levers, an auxiliary rod carried by each of the first named rods and movable longitudinally with relation thereto, and yielding means to oppose relative longitudinal movement of the auxiliary rod, a pair of spaced
- 55 shoes carried by each auxiliary rod and adapted to engage upon opposite sides of the corresponding actuating lever to shift said auxiliary valve.

In testimony whereof I affix my signature.
